UNITED STATES PATENT OFFICE.

HAROLD M. DAVIS, OF ELIZABETHTOWN, NEW YORK.

GREASE-GUN.

1,165,156.

Specification of Letters Patent. Patented Dec. 31, 1915.

Application filed October 6, 1914. Serial No. 865,233.

To all whom it may concern:

Be it known that I, HAROLD M. DAVIS, a citizen of the United States, and a resident of Elizabethtown, in the county of Essex and State of New York, have invented certain new and useful Improvements in Grease-Guns, of which the following is a specification.

My invention relates to lubricant containers particularly adapted for use on vehicles, such as automobiles, and having especial reference to the lubrication of leaf springs, and the main object thereof is to provide such gun which is adapted to be inserted between two leaves of such springs after they have been separated by means of a suitable implement or tool and from which the lubricant may be forced in desired quantity and at desired points by one hand of the operator; a further object is to provide a special tip for such use which insures the delivery of ribbons of lubricant of uniform thickness, whereby a thin film of the lubricant is deposited upon one or both of the separated leaves; a further object is to provide simple and efficient means for re-charging said gun with lubricant; and still further objects are to provide such guns which are simple in construction and use, well adapted for the purpose for which they are designed, positive in and easy of operation, and comparatively inexpensive.

My invention is fully described in the following specification, of which the accompanying drawings form a part, in which the separate parts are designated by the same reference characters in each of the views, and in which:

Figure 1 is a side elevation of a grease gun constructed in accordance with my present invention; Fig. 2 is a top plan view thereof; Fig. 3 is a fragmentary detail section taken on the line 3-3 of Fig. 1; Fig. 4 is a side view of a modification of a gun tip which I employ; Fig. 5 is a longitudinal, vertical, section taken through the gun, empty, and in extended position of the parts; Fig. 6 is a similar, fragmentary, section, showing my means for filling the grease gun; Fig. 7 is a detached, perspective, view of the filler; and Fig. 8 is a detached view of a paddle which I employ in connection with said filler.

In the drawings forming a part of this application I have shown one form of embodiment of my invention, comprising a cylindrical barrel 9 having a discharge tip 10

threaded upon one end and a bored head 11 threaded into the opposite end and through which passes a rod 12 carrying a suitably packed piston 13 upon its end within the barrel, said tip 10 being divided into compartments by means of a partition 14 and having discharge ports 15 and 16 for said compartments, and, by reference to Fig. 2, it will be noted that the tip is of relatively slight thickness with respect to its width, to enable it to be inserted between the leaves of a spring.

Surrounding the piston-rod 12 is a tube 17 threaded into the barrel head 11 at one end and secured to an arm 18 at its outer end and which arm is secured to a slotted guide 19 for a sliding rack 20 having a downwardly directed arm 21 secured to the outer end of the piston-rod 12, the tube 17 being slotted at 22 to permit the movement of said arm 21, and it will be seen that, when the rack 20 is actuated forwardly in a manner to be explained, the piston 13 is forced forwardly to expel the grease from the barrel 9.

Pivoted at 23, to the guide 19 in the form shown, is a forked lever 24 extended rearwardly over said guide and the contained rack 20, and the rear end of which is spoon shaped to serve as a rest for the thumb of an operator, a grip plate 25 being provided beneath the tube 17 for the fingers of the same hand whereby the device may be held and manipulated with one hand; an inwardly directed pawl 26 is pivoted to the lever 24, between the forked tines thereof, at 27, and the inner end of which is maintained in engagement with the teeth of the rack 20 by means of a spring 28, and it will be seen that, if the lever 24 be manually reciprocated, the piston 13 is forced forwardly, step-by-step, and the amount of grease being expelled is thus under positive control and requiring but one hand of the operator instead of, as in the conventional grease guns, requiring one hand to hold the barrel and the other to actuate the piston.

In view of the fact that I desire to expel the grease in a thin ribbon of considerable width, and the fact that if but one discharge slot be provided the grease will only exude from the gun adjacent the forward closed end of the tip 10, I provide the partition 14 and two discharge slots, or possibly more partitions and slots, in order to equalize the pressure along the full length of the tip,

a plurality of relatively narrow ribbons of grease resulting which, however, merge into one ribbon exteriorly of the tip.

In Fig. 4 is shown a slight modification of 5 the discharge tip wherein the flat portion 29 is arranged perpendicular to the axis of the barrel, and I will provide both forms of tip with each gun vended.

In Figs. 6, 7 and 8, I have illustrated a 10 means for recharging the grease gun barrel 9, comprising a cylindrical, open-ended, filler 30 having a handle 31 and a longitudinal slot 32, and adapted to be forced into the grease in a pail or other original container 15 and rotated therein to fill the same, after which said filler is inserted into the barrel 9, the tip 10 having been previously removed, the external diameter of said filler approximating the internal diameter of the barrel, as shown in Fig. 6; when said filler 20 has been charged with the lubricant, a paddle 33 is forced through the slot 32 thereof and rotated through an arc of 90 degrees of a circle, thus bringing said paddle into 25 transverse relationship with said filler, this being as close to the handle 31 as is possible, after which said filler is moved entirely within the barrel, the handle 31 grasped with one hand and the handle 34 of the 30 paddle with the other hand and said filler is forcibly drawn out of the barrel while the paddle is maintained in close proximity to the end of said barrel, and this discharges the lubricant from the filler and into the barrel; when the filler has been so removed 35 from the barrel, the tip 10 may be replaced and the gun is then ready for use, and it

will be noted that the operator need not soil his hands at any stage of the charging or discharging of either the filler or the gun 40 barrel.

While I have shown and described certain details of construction, it will be understood that I do not limit myself thereto, but may make changes thereover, and modifications thereof, within the scope of the following claim, without departing from the spirit 45 of my invention, or sacrificing its advantages.

Having fully described my invention, 50 what I claim as new, and desire to secure by Letters Patent, is:—

A grease gun, comprising a barrel, a discharge tip thereon, a piston therein, a rod 55 connected to said piston and extending out of said barrel, a slotted tube inclosing said rod and in detachable engagement with said barrel, an arm carried by said rod and slidable in said slot of said tube, a rack carried by said arm exteriorly of said barrel, a guide for said rack connected with said tube and with said barrel, and a manually operable pawl in pivotal connection with said guide adapted to move said rack 60 step by step to correspondingly force said piston toward said tip.

In testimony whereof I have signed my name to this specification in the presence of two subscribing witnesses.

HAROLD M. DAVIS.
